(57) **CLAIM**

The ornamental design for an electric lawn mower as shown and described.

DESCRIPTION

FIG. 1 is a front perspective view of the electric lawn mower;

FIG. 2 is a back perspective view of the electric lawn mower;

FIG. 3 is a front view of the electric lawn mower;

FIG. 4 is a back view of the electric lawn mower;

FIG. 5 is a right side view of the electric lawn mower;

FIG. 6 is a left side view of the electric lawn mower;

FIG. 7 is a top view of the electric lawn mower; and,

FIG. 8 is a bottom view of the electric lawn mower.

The broken lines are for illustrative purposes only and form no part of the claimed design.

1 Claim, 8 Drawing Sheets

FIG. 2

FIG. 3

FIG. 4

FIG. 5

FIG. 6

FIG. 7

FIG. 8
